(57) **CLAIM**

The ornamental design for a portable computer, as shown and described.

DESCRIPTION

FIG. 1 is a front view of a portable computer;

FIG. 2 is a rear view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view of the portable computer in opened status; and,

FIG. 8 is a perspective view of the portable computer in closed status.

The broken lines showing of the portable computer are for the purpose of illustrating and form no part of the claimed design.
